UNITED STATES PATENT OFFICE

2,549,446

HAIR CURLER

Samuel Frishberg, New York, N. Y., assignor to
 Delamere Company, Inc., Jersey City, N. J., a
 corporation of Delaware

Application March 12, 1949, Serial No. 81,203

4 Claims. (Cl. 132—40)

1

This invention relates to a hair curler of the mandrel or winding form type intended to be worn temporarily in the hair to form a curl.

One object of the invention is to provide a hair curler of the mandrel type having hair-engaging teeth that operates effectually to wind the hair in a curl.

Another object is to provide a hair curler of this type that is easy to manipulate.

A further object is to provide a curler of light weight that may be comfortably worn in the hair.

A still further object is to provide a hair curler that is simple and inexpensive to manufacture.

With these, and other objects in mind, the invention will appear clearly from the following description thereof, reference being had to the accompanying drawings, in which:

Fig. 1 is a front elevation of the hair curler;

Fig. 2 is a bottom view;

Fig. 3 is an end view;

Fig. 4 is a section on line 4—4 of Fig. 1; and,

Fig. 5 is a section on the line 5—5 of Fig. 2.

The hair curler comprises a longitudinal flexible member 10 of greater width than thickness provided with opposed sets of teeth 11 along the central portion of its upper and lower edges. The member 10 may be made of flexible plastic material, rubber or other suitable substance, and it has a pliable metal strip or wire 12 extending lengthwise therethrough.

A spool 13 which may be made of aluminum or lightweight, non-corrosive metal or other material is supported on and about the member 10 intermediate the ends 14 of the latter which ends project outwardly beyond the corresponding ends of the spool. The surface of the spool is preferably, though not necessarily, concave or incurved as shown in the drawings, and it may be formed with perforations 15.

The spool is formed from a blank of metal which blank has a slot 16 therein that corresponds in dimensions with the length and thickness of one of the sets of teeth. In manufacture or assembly the teeth of one set are passed through the slot and the blank is rolled or bent around the central portion of the member 10. The two edges of the blank that form the joint 17 when the blank is rolled into shape are provided with notches 18, which notches combined form an opening corresponding to the slot 16, through which opening the teeth of the second set project. It will be seen that the spool 13 is held in fixed position in relation to the member

2

10 by reason of the fact that the teeth of the latter pass through the openings in the spool as best seen in Fig. 5.

In use the end or the lock of hair to be curled 5 is engaged in the teeth and is wound about the spool, after which the ends 14 of member 10 are bent over to hold the device in place and prevent the hair from unrolling.

On reference to Fig. 3 it will be noted that 10 the spool 13 is hollow and spaced from the two sides of member 10. This permits of circulation of air through the center of the spool while the hair is wound thereon and thus facilitates rapid drying of the hair and formation of the curl.

15 While I have described and illustrated a preferred form of the device, it is to be understood that various modifications may be made thereof within the spirit and scope of the invention.

I claim:

20 1. A hair curler comprising a longitudinal pliable member having teeth along the central portion of its upper and lower edges, and a hollow rigid spool member mounted on the central portion of the longitudinal member with the ends 25 of the latter extending outward beyond the respective ends of the former, said spool member having openings through which the teeth of the longitudinal member project.

2. A hair curler comprising a longitudinal pliable member having teeth along the central portion of its upper and lower edges, and a hollow spool member having a concave peripheral surface mounted on the central portion of the longitudinal member with the ends of the latter extending outward beyond the respective ends of 30 the former, said spool member having openings through which the teeth of the longitudinal member project.

3. A hair curler comprising a rigid hollow spool member, and an elongated flat pliable member extending longitudinally through the spool member, said spool member being mounted on the pliable member and spaced from the sides thereof to provide open ended air passages between said members, said pliable members having teeth on 35 its upper and lower edges which teeth project through openings in the spool member.

4. A hair curler comprising a longitudinal pliable member of greater width than thickness having teeth along the central portion of two opposite edges, and a hollow metal spool mounted on and about the central portion of said pliable member, said spool having openings at opposite points of its surface through which openings the teeth project, said openings being of substan-

3

tially the same width and breadth as the teeth so that engagement of the teeth in the openings holds the spool in fixed position relative to the longitudinal member.
